UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

CIRCULAR-KNITTING MACHINE.

1,272,865.

Specification of Letters Patent. Patented July 16, 1918.

Application filed December 19, 1914. Serial No. 878,007.

To all whom it may concern:

Be it known that I, ROBERT W. SCOTT, citizen of the United States, and resident of Boston, in the county of Suffolk and State 5 of Massachusetts, have invented certain new and useful Improvements in Circular-Knitting Machines, of which the following is a specification.

My invention relates to circular knitting 10 machines of the independent needle type, and particularly to such machines adapted for the automatic production of articles of hosiery, such as stockings.

One object of my invention is to improve 15 the operative capacities and the mechanism of hosiery knitting machines of the type disclosed and claimed in my applications Serial Number 746,070 filed February 3, 1913 (Letters Patent No. 1,152,850, dated September 7, 20 1915) and Serial Number 766,401 filed May 8, 1913 (Letters Patent No. 1,148,055, dated July 27, 1915).

In the accompanying drawings,

Figure 1 is a plan taken above the bed 25 plate and partly in horizontal section of a machine corresponding to my invention, the needle cylinder and attached parts being removed;

Fig. 2 is a vertical section on a line 2--2 30 of Fig. 1;

Fig. 3 is an elevation partly in section illustrating some of the connections to the pattern mechanism;

Fig. 4 is a diagram plan view showing one 35 form of the supplemental cams;

Fig. 5 is a diagram illustrating a typical set of indications carried by the pattern surface;

Figs. 6 to 13 inclusive are diagrams illustrating the operation of another form of the 40 supplemental cam devices in co-operation with the needles and the jacks;

Fig. 14 is a detail illustrating two different kinds of jacks;

Fig. 15 is a similar figure illustrating three different kinds of jacks;

Fig. 16 is an internal development of the cam ring, illustrating one use of jacks of two different kinds;

Fig. 17 is a similar view illustrating one use of jacks of three different kinds;

Fig. 18 is a detail section on line 18—18 of Fig. 1;

Fig. 19 is a detail showing another form of cam for operating the slide 2. 55

The construction and operation of the machine may be the same as that disclosed in my said applications except as below specified, and I have not disclosed herein the means for supporting and driving the parts, 60 for adjusting the length of stitch, for determining rotary or oscillatory movement of the needle cylinder, for narrowing or widening the knit tube, or for handling, feeding, changing, cutting and clamping the yarn or 65 yarns, except incidentally. While I have illustrated the parts mentioned below of the machine of my said prior applications, it will be understood without further explanation that the devices about to be described 70 are applicable to existing machines of many different types, and that my invention is not restricted to the use of the device of the present application in the particular machine shown.

In the said illustrative machine, a needle cylinder 260 is supported for limited vertical movement upon a bearing ring 257 carried by a tubular column 280, said cylinder resting upon pins 256 housed in vertical 80 bores in a bevel gear 30 operated by a similar gear fast on a main shaft 32, Fig. 3.

Motion of the gear 30 is imparted to the cylinder 260 by a gib or key 252 carried by an attachment of said gear. Said cylinder 260 carries an attached web-holder dial 295 upon which rotates a web-holder cam cap 300, having attached thereto cams for operating independently movable web-holders 292 taking between needles n , which may 90 have the usual operating butts, comprising long butts n^1 and short butts n^2 , for the usual stocking knitting purposes.

The machine construction also comprises a latch guard ring 550 surrounding the 95 heads of the rotating needles, a series of yarn changing yarn guides F, and means for operating the yarn guides and some other agencies of the machine consisting of a series of thrust bars 460 in contact at their 100 lower ends with a pattern surface 120.

Narrowing pickers 650, a widening picker

680 and internal yarn cutter and clamp mechanism 601 may form a part of the machine but are no part of my present invention except as elements of the general combination for knitting stockings.

As set out in my said application Serial No. 766,401 the machine illustrated comprises means for beginning to knit upon needles bare of previous fabric, and for operating the needles when desired to withhold the loops last formed upon recurrent needles of the series, in order to knit fabric upon the remaining needles to form an out-turned welt and certain other useful structures. In the said machine these operations are performed by mechanism separating the needles into two or more intercalated series and means for acting upon a set of needles so separated to determine a movement different from the movement made by the needles of the other set. As disclosed in my said application the needles intended to withhold the loops, or to stand out of the operative series when first receiving yarn, or to retain the loops over an intervening course or courses, were retracted by a supplemental cam 382 (Figs. 16 and 17) into an idle groove 10, carrying the heads of the needles below the place of supply 560 of the knitting yarn. This movement was effected with respect to needles normally traveling at the tuck point *i. e.* with their previous loops resting upon their opened latches and not cleared beneath said latches. Being without the provision of any means to clear the latches of selected needles only and to then retire said needles, said machine was incapable of operating a selected set of needles so as to cast off stitches once formed upon the needles, the casting-off means disclosed therein consisting of devices to remove the yarn from contact with all of the needles, during normal operation of the needles cleared at or near the stitch-making point.

I have now devised means for knitting in succession sections of plain fabric each containing the same number of needle wales, said means providing for the continuity of the fabric where the change is effected. Such fabrics may be characterized by needle wales of one section corresponding to sinker wales of another section, and the said means therefore enable the needles to be selectively operated upon so as to determine knitting upon some of them, said needles also being capable of actuation to withhold their loops; and to determine knitting upon other needles, said other needles being capable of being cleared and then retracted to cast off a previous loop. As will appear below I have also provided a machine of increased capacity with respect to the different kinds of fabric which may be formed automatically during a continuous operation or each opera-

tion of a succession of operations to produce articles having said different kinds of fabric integrally formed in succession therein, the new devices adapting the said machine to the formation of beginning selvages of a desired kind, to the production of a welt knit upon relatively as large a number of the needles as those knitting the attached and following fabric, and to the production of improved forms of uniting structure for the welt fabric and fabrics suitable for the tops or cuffs of garments; and to other improved functions.

Referring now to Fig. 16 the machine is provided with a top center cam 8 and a bottom center cam 9 carried by a cam ring 271, of which a segment 370 may be removable. Said segment carries the usual stitch cams 6 and 7.

A switch cam 415 operating in connection with a fixed guard cam 411 is mounted for rotation on a radial spindle 410 carried in bracket 408, for the usual purpose of elevating series of needles having long butts ^{n¹} above the stitch cams during reciprocal knitting on the remaining needles, and for returning all of the needles to their normal level, which is that of the ledge 40.

Preceding the leading end of that stitch cam 7 first encountering the needles when the machine is rotating for tubular work, the cam 382 of my said applications is provided to be radially moved into and out of contact with such needle butts as are traveling at a level to encounter it. When said cam is in contact with the needle butts they are retracted into the idle groove 10 under leading stitch cam 7 and under the bottom of said cam 9, all of said needles being returned at each passage of the cams by the slope 5 to the normal position at the level of the ledge 40.

In order to separate the needles, for instance into two intercalated series, certain of them are provided with independently movable jacks ^{j¹}, ^{j²}, placed in the needle groove underneath the selected needle, said jacks having operating butts taking into a cam groove or grooves for moving the selected needle from its normal level above a level in reach of the cam 382. The present machine is provided with two such grooves as shown at 364, 365, Fig. 16, and I may employ in connection therewith a series of jacks ^{j¹} coöperating with the upper groove 120 365 and a series of jacks ^{j²} coöperating with the lower groove 364.

The groove 365 is provided with a cam apex 367 preceding the location of the cam 382. Said groove is also provided with a depression 368 for a purpose presently to appear. The cam groove 364 is provided with a cam 366 coöperating with the butts of the jacks ^{j²}. The apex of the cam 366 precedes by a considerable distance the apex 130

367. The jacks j^3 are longer than the jacks j^1 , and the relative height of the cam 366 and the apex 367 is such that the needles provided with jacks j^3 are elevated above 5 their normal level to a height at which their latches are cleared through their previous loops, for instance to the same height as that attained by the advancing surfaces of the stitch cams 6 and 7.
- 10 Needles provided with jacks j^1 are advanced at the apex 367 through a lesser distance, for instance corresponding to a height midway between the normal level of the needles and the height to which the needles 15 are elevated to clear their latches.
- Needles traveling at a normal level are in a position to be advanced by the leading stitch cam 7 except when the cam 382 is inserted.
- 20 In that arrangement of the changeable jacks illustrated in Fig. 16 alternate needles are provided with jacks j^1 and j^3 , so that each needle has a jack. In the absence of the cam 382, the needles will be normally 25 operated at the stitch cams, the jacks j^3 elevating the needles sufficiently to clear their latches at an early time, but having no other effect.
- When cam 382 is inserted the needles having the jacks j^1 will be retired into the idle groove beneath the bottom center cam without having been advanced to clear their latches.
- Coöoperating with the needles and with 35 the jacks there are additional supplemental cams 2^a and 2^b removably screwed to the T-shaped head of a substantially radial slide 2, which coacts with means again mentioned below to move said slide inward to a greater 40 or less distance. The cam 2^a extends downwardly from a point following the line of movement caused by the jacks j^3 and cam 366, in order to depress such needles as encounter it beneath the level of the ledge 40 into a depression 11 of the cam ring and, 45 into a position at which said needles will not encounter an advancing surface at the stitch cams but will pass into the idle groove. Needles which have been advanced by a jack 50 j^3 and have therefore cleared their loops will, upon encountering cam 2^a thus be depressed to cast off their previous loops, for instance at the lower apex of the cam 7.
- The cam 2^b is an advancing cam of sufficient 55 height to encounter needles moving at a level of the ledge 40 and to advance them above the cam 382, but said cam 2^b is insufficiently high to encounter needles traveling at a level attained by those moved by 60 the jacks j^3 .
- Needles which are provided with jacks j^1 , when the cam 2^b is in an operative position, while they are depressed by the cam 2^a , are again advanced by the cam 2^b , passed over 65 the cam 382, if it should be in an operative position, to then enter the stitch cams and knit normally.
- It will be seen that with the cams 382, 2^a , 2^b out of contact with the needle butts, all of the needles will enter the cams and knit; 70 when the cam 382 alone is inserted to an operative position the needles having the jacks j^1 will be depressed beneath the stitch cams, without having cleared their loops, at each revolution; and when the cams 2^a and 2^b are in an operative position needles provided with the jacks j^3 will cast off their previous loops while needles provided with the jacks j^1 will enter the cams and knit. When the cams 2^a and 2^b are operative, the 75 cam 382 is out of possible contact with any of the needle butts and may be removed without effect upon the operation.
- The machine is provided with means for independently moving the cam 382, and the 80 slide 2 and attached parts 2^a and 2^b substantially radially with respect to the needle cylinder at the desired times. It will be understood without further description that a great variety of operations may be performed, depending upon the particular arrangement of the jacks j^1 , j^3 and the particular order of actuation of the cams 382 and the compound cam made up of the cams 2^a and 2^b . For instance, in order to knit one of 85 the fabrics illustrated in my Letters Patent No. 1,113,166, dated October 6, 1914, which product briefly comprises a stocking or sock having a welt, an attached mock-rib top and the usual leg, heel, foot and toe, the welt 90 fabric having as many wales of knit loops as the attached fabric, and a structure at the junction of the welt and the attached fabric of improved strength and elasticity, the needle and jack arrangement illustrated 95 in Fig. 16 is preferable. The operation may begin on the bare needles, and for this purpose the cam 382 may be inserted prior to the feeding of any yarn for the beginning 100 of a new article, thereby permitting the needles with long jacks j^3 to pass through the knitting cams, in a position to take the new yarn when fed from the yarn feed throat 560, the said active needles traveling in the groove between the top center cam 105 8 and the cotton center cam 9. The alternate needles provided with the short jacks j^1 pass in the idle groove 10 under the cam 9. Said needles with short jacks will not be advanced far enough to pass above the down 110 going face of the cam 382. The initial yarn having been fed to the needles, and placed under stress and restraint with respect to their knitting movement at the cams 6, 7 and 8, in the same manner as disclosed in 115 my Patent No. 1,094,347, April 21, 1914, reissued No. 13,752 June 16, 1914, (as by timing the operation of the web-holders 292, for instance by the means described and 120 claimed in my said application Serial No. 125 130

766,401) the second course normally taken by the needles will now be drawn alternately in front of and behind the first course, to make a selvage structure such as that 5 illustrated in my Patent No. 1,045,621 dated November 26, 1912, and in my said reissued Letters Patent No. 13,752.

The laying of the second course on all the needles may be accomplished by withdrawing 10 the cam 382.

This withdrawing movement may be in two stages, the first stage removing the cam during the passage past it of the long butt needles n^1 to a position to run off the end of 15 the series of long butt needles, and the second movement occurring before the long butt needles have again reached the cam.

The fabric for the welt is now to be knit upon one series of the needles, those with 20 long jacks j^3 , while the other series pass the stitch cams at each course in the idle groove 10 while retaining withheld loops to unite the beginning of the welt to the attached fabric. These loops are to be withheld from 25 the second or a following course. The withdrawal of the cam 382 having permitted all of the needles to take yarn, and established a second course at least once around the entire set of needles, said cam may now be re- 30 inserted to cause the short jack needles affected by it to withhold their loops. The operation to withhold loops may begin at the leading needle n^{10} having a long butt n^1 , and for some articles it is not detrimental 35 thus to twice include the long or the short butt needles among the entire series of needles n^1 and n^2 knitting previously to the beginning of the welt. For instance, referring to Fig. 4 of my said Patent 1,113,166, 40 loops may be withheld from the second course on all of the long butt needles, and from the third course on all of the short butt needles, all of the needles having taken yarn and made a knitting movement during 45 one and one-half revolutions of the needle cylinder. So forming the course of loops withheld on recurrent needles economizes movement of the cams. The cam 382, having been moved out to position II, Fig. 4 50 to run off the end of the long butts, permitting the short butts n^2 all to knit, is then moved out to position I to permit the long butts (and at the next passage the short butts) to knit; and is then moved in to position 55 II prior to the second passage of the long butts to begin the withholding of loops at the leading long butt short jack needle n^{10} , moving all the way in to position III prior to the passage of the short butts. 60 Movement of cam 382 is thus made in two stages II and III in advance of its position of rest I.

The welt fabric is now knit to the desired extent upon the needles provided with jacks 65 j^3 without again disturbing the cams.

In the arrangement shown in Fig. 16 these needles are not capable of being retired into the idle groove 10 while holding their loops, the action of the jacks j^3 being such as to clear their previous loops beneath the latches 70 at the apex of the cam 366, prior to reaching any of the supplemental cams 382, 2^a or 2^b.

The welt is now completed by knitting a uniting course upon all the needles. This is accomplished by the same adjustment as 75 for the course of withheld loops, i. e. by withdrawing the cam 382 in two stages, to permit the leading short butt and the following series of long butts to knit at least one course of fabric having needle loops taken at each 80 needle. Such loops as are formed on the short jack needles penetrate and cast off the withheld loops of the second or third course by which the beginning edge of the welt has been held at the needles during the preceding operation, thus joining the beginning of the welt to the end thereof and to the subsequent fabric.

In a great many situations, for instance 85 for tops or cuffs of garments, or for a welted garment, of which all parts shall be capable of like lateral stretching, it is desirable to have all parts of the fabric of relatively the same number of wales in width. Having, in order to retain the beginning edge of the 90 welt, retired certain needles, and having restored them to action for a uniting course or courses, I now retire empty a number of needles, preferably those engaged in forming the welt, to enable the knitting of attached fabric upon the remaining needles only. It will not ordinarily be objectionable 95 to follow the uniting course taken on all of the needles, with a course or courses taken on all of the needles, nor will it be objectionable to knit an additional course upon the short butt or the long butt needles only. At the part of the fabric occupied by said 100 needles, knitting of the uniting course may therefore be accomplished simply by removing cam 382 as before to run off the end of the long butt series and again inserting said cam after their next passage. This will permit 105 the short butt needles having the jacks j^1 to knit twice. The arrangement is now the 110 same as during the knitting of the welt, and fabric upon those needles having long jacks j^3 only may now be formed to a desired extent, the needles having short jacks j^1 again holding all of their loops. The purpose of 115 the fabric being knit upon the long jack needles is to fasten off wales which are about to be suppressed, prior to retiring the long jack needles after casting off their last loops during knitting of a part or all of the subsequent fabric.

To resume knitting on the short jack needles and cast off on the long jack needles the slide 2 is inserted, its down-going incline 2^a carrying the needles with the long jacks 120

into the depression 11 and under cams 7 and 9 after their loops have been cleared beneath their latches. The cam 2^b operates at the same time to mask and render ineffective the 5 action of the cam 382, the short jack needles now rising at apex 367 in time to encounter the advancing face of said cam 2^b, and thence going into the stitch cams to knit. Movement of slide 2 and cams 2^a and 2^b for these 10 purposes is in two stages II and III, Fig. 4, in advance of a position of rest I.

One effect of casting-off the terminal stitches of wales knit by the long-jack needles is illustrated in Fig. 5 of my said 15 Patent, No. 1,115,166, the natural curl forward of the fabric toward its wrong side, which is that lying upward at the needles, being then permitted to carry the loops cast off forward over the heads of the needles 20 upon which said loops were formed whenever said needles are withdrawn into the idle groove 10. Since the needles so operated recur among the other short-jack needles now knitting, such movement forward of the terminal 25 loops of the wales cast off will cause said loops to stand between the active needles, there to be tied down by the new yarn knit by the intervening short-jack needles. The terminal loops are thus passed forward toward the face of the fabric, to be 30 frictionally held between sinker wales of the fabric knit by the needles having short jacks. This operation is aided by the movement of the web-holders above referred to, 35 which is a withdrawing movement taking place after all or a part of the movement of the needles down the slope 8^a of cam 8, the cast-off loop following the retiring web-holder through the gap in the needles just 40 prior to the knitting movement of the needles of the other (short-jack) series.

In order to adapt the machine devices to the making of structures begun and ended upon the same adjacent or near-by pair of 45 needles, for instance upon the first or leading long butt needle n^{10} of the series n^1 and the last or following short butt/needle n^{20} of the series n^2 respectively, I have illustrated means to prevent cam 382 from acting on 50 the long butt needles a second time after its insertion to move all of the needles with short jacks once only. One device for this purpose, illustrated in Figs. 6 to 13, comprises an elongated cam 2^b, so positioned 55 with respect to the slide 2 of the cam as to enable cam 2^b to encounter and advance the long butt needles when the slide 2 is in a position in which the depressing member 2^a is still out of contact with the needles.

60 Referring now to said figures, which also illustrate conventionally the arrangement of the jacks j^1 and j^2 with respect to the needles, Fig. 6 illustrates the position of the cams 382, 2^a and 2^b when yarn is first given to the 65 needles to initiate knitting. The needles

provided with the short jacks j^1 , beginning with the leading long butt needle n^{10} are shown as beginning to pass down the face of cam 382 which, during the first passage of the long butt needles n^1 will move into the 70 position shown in Fig. 7 so as to affect the short butt needles. Fig. 7 illustrates the position of the devices after movement substantially of one whole revolution of the needle carrier at the beginning of a course 75 taken by all of the needles. During the second passage after beginning to feed yarn of the short butt segment past the faces of cams 2^a and 2^b, said cams are moved inward to the position shown in said figure, thereby 80 to engage the cam 2^b under the leading long butt needle n^{10} having a jack j^1 . The needles having jacks j^2 , it will be understood, were passed above the level of cam 2^b or cam 382 at a point corresponding to the jack cam 85 366. The effect of the cam 2^b is to restore the short-jack long butt needles to knitting, to form a course on all of the needles beginning at the leading long butt needle n^{10} . During the passage of the long butt needles, 90 the cam 382 having been rendered ineffective by the presence of cam 2^b, may be removed to the position shown in Fig. 8, whereupon the short butt needles will pass across the face of the cam 382, up the slope 7^a of the 95 leading stitch cam 7, and into the stitch cams. When the last short butt needle n^{20} has so moved into the cams, one complete course on all of the needles will have been formed. It is now desired to begin making a welt upon 100 the needles having long jacks only.

The cam 2^b having served its purpose of taking the long butt needles only over the cam 382, will be removed after the first passage of the long butts to the position shown 105 in Fig. 8.

Cam 382 must now become active in order to knit the welt upon the needles having long jacks j^1 . For this purpose the position to which it was removed during the knitting 110 of the course of withheld loops upon all of the needles (Figs. 7 and 8) need not be changed, the cam remaining as shown in Fig. 8, to engage and take down all the long butt needles having short jacks j^1 , again beginning at needle n^{10} .

During the first passage of the long butts cam 382 will be moved all the way in as indicated by the arrow thereon in said Fig. 8, and for the remainder of the welt no further change in the adjustment of the cams is necessary.

Enough fabric having been knit upon the needles with long jacks, during the retention of the withheld loops by the needles with short jacks passed beneath the stitch cams by cam 382 it is now desired to begin the uniting course upon the same needle n^{10} as that upon which the knitting was initiated and the changes instituted for the prior op- 130

erations. The uniting course being a course taken upon all of the needles, cam 2^a is now positioned as shown in Fig. 9 during the passage of the short butts. This position and its effect is the same as that described in connection with Fig. 7. Sufficient fabric having been knit (usually one course, although I may if desired knit several courses at this point on all the needles) knitting is now to be resumed upon the same (long jack) needles as were employed in the welt, to lock the fabric from raveling back and releasing the uniting course. This operation is the same as that for the welt, and the cams will therefore again be positioned as shown in Fig. 10.

It is now desired to cast off the terminal loops corresponding to the wales of the welt fabric, to retire the needles upon which the welt was formed, and to continue the fabric upon the remaining needles. The cams 2^a and 2^b are therefore operated to cast off the terminal loop in the courses last knit and to cause knitting in all the wales containing loops withheld on the needles having short jacks. This is done by moving in the cams 2^a and 2^b during the passage of the short butts far enough to engage depressing surface 2^a with the leading long butt long jack needle (Fig. 11) which having been cleared by its jack, casts its loop upon being sufficiently retracted, for instance at the lower apex of the cam 7. As shown in Fig. 11, cam 2^a may be entered upon the needles in the position there shown and then moved all the way in, to affect the short butts, to the position of Fig. 12, after sufficient needles have passed its face, and during the passage of the long butts.

This operation of cams 2^a and 2^b takes place simultaneously with or prior to the withdrawal of the cam 382, the effect of the cams 2^a and 2^b being to prevent any operative function of the cam 382, and said cams 2^a and 2^b preceding the cam 382, the entry of slide 2 will secure without further provision the restoration to knitting of the short jack needles knitting the wales containing withheld loops, and casting off at the long jack cast-off needles.

For knitting a stocking top or other extent of fabric on the short jack needles only, cams 2^a and 2^b are left in the position shown in Fig. 12. At the end of the desired quantity of fabric on the short jack needles only, cams 2^a and 2^b may then be positioned during the passage of the long butts as shown in Fig. 13, preparatory to running off the end of the long butt series, and the withdrawal of said cams to the position of Fig. 6 at the ensuing passage of the short butts. When cam 2^a is in use, it will be understood that all of the needles having butts in reach of its surface are depressed, including such as have short jacks, but such needles are

again raised at apex 367 of the upper jack groove 365. To permit the free movement of jacks j^1 , the depression 368 is formed in groove 365 at the location of cam 2^a.

While I have described alternate needles provided with jacks respectively controlled by grooves 364 and 365, it will be understood that the arrangement of jacks is changeable to produce desired variations in the fabric. Some of the needles, for instance, might not be provided with jacks, thereby permitting cam 2^a to withhold loops on these needles while casting off on the long-jack needles; or the long and short jacks might alternate in groups of two or more, or otherwise be arranged with reference to the desired operation obtainable by moving cam 382 and slide 2 at independent predetermined times.

Neither is my invention limited to an alternate arrangement of long and short jacks. Having separated the jacks into two independently actuated series, I am still enabled to provide jacks of different kinds in one or both of said series, to thereby further separate the needles for any desired purpose, such as their different actuation at the supplemental cams 2^b or 382, for example to take out of action during subsequent knitting some only of the needles engaged in knitting the welt fabric.

For instance, as shown in Fig. 17 jacks j^2 of intermediate length, see Fig. 15, may be supplied in the upper groove 365 at the location of recurrent needles, such as every fourth needle, needles on each side of the needles with the medium length jacks being supplied with short jacks j^1 , and the intervening needles being supplied with long jacks having butts working in the groove 364.

The medium jacks j^2 are of such a length as to cause the needles moved by them at the apex 367 to be carried above the cam 382. Needles supplied with such jacks are therefore ever-active, their jacks inevitably taking them into the knitting cams, whatever the position of the supplemental cams 2^a, 2^b and 382.

With cam 382 in, alternate needles supplied with jacks j^1 may be passed beneath the stitch cams to withhold their loops, or stand out of the series first given yarn to form a set-up or selvage course or make a line of draw-strokes. Said cam 382 may therefore be operated with respect to the short-jack needles, to permit all of the needles to take yarn, or to withdraw the short jack needles, movement of the cam occurring as described in stages permitting entrance and exit at the beginning and end of the long butt series of needles.

By operation of slide 2, the needles with long jacks j^3 are either permitted to knit or caused to cast off. The particular arrangement illustrated in Fig. 17 as an instance of

many variations of distribution of jacks of three lengths, is such as to enable a selvage to be begun on the long jack and medium jack needles, together constituting half of 5 all the needles, arranged alternately with short jack needles making up the remainder. A second course can be knit on all the needles by withdrawing cam 382, and may be confined to one round of the needles only 10 by the use of cam 2^b, as described in connection with Figs. 6 to 13 above; a welt may thereafter be knit on the long jack and medium jack needles; a uniting course may be formed on all the needles, and locking 15 fabric then knit on the needles employed in the welt, the short jack needles holding their loops (cam 382 then being in operation); and the long jack needles may then be operated to drop their stitches, to stand out of 20 the subsequent fabric so long as cam slide 2 remains in its active position.

It is obvious that long jacks may be supplied to obtain any desired drop stitch arrangement. For the particular purpose of 25 providing an alternation of needles for selvaging or welting, every alternate needle being provided with a short jack in groove 365 either a long or a medium jack may be supplied for any remaining needles, thus to 30 control the location at alternate wales in the fabric of solid knitting or drop-stitch wales capable of being begun and ended at any point in the fabric.

The devices for supporting and operating 35 cams 382 and cam slide 2 may be broadly the same as those disclosed and claimed in my said application Serial No. 766,401, comprising a bracket 19 fastened on bed plate D having slideways formed therein for slide 40 2 and for cam 382, spring plungers (not shown) tending to hold said slide and said cam outward. Bracket 19 also provides a bearing boss for a pivot screw 488 and lever 487 in contact at one end with cam 382 and 45 at the other end with a cam 485 on one of the thrust-bars 460. A similar bearing boss is provided on bracket 19 for pivot screw 21 and lever 20 taking at one end against slide 2 and at the other end against a cam 50 50 attached to an additional thrust-bar 26 having a sliding bearing in a plate 28 attached to bracket 19.

The thrust-bars 460 and 26, as shown in Fig. 3, rest at their lower ends against a 55 pattern surface such as drum 120 rotatable on stud shaft 76, as by gearing 121, 122, 123 from a main pattern shaft 80. Drum 120 is also capable of being moved in time with the passage of particular parts of the needle 60 carrier 260 at the supplemental cams by an auxiliary pawling mechanism 431, 432 actuated by a cam 430 on main shaft 32. This auxiliary pawling mechanism is rendered active whenever the shaft 80 has advanced 65 teeth 434 into range of pawl 432, whereupon

drum 120 is moved intermittently forward during certain quadrants only of the rotary motion of cylinder 260, such as when the middle of the long butt needles and the middle of the short butt needles are opposite 7 cams 382, 2^a and 2^b, the pattern surface 120 remaining at rest during the passage of remaining segments of the needles.

The timely movements of cam 382 and slide 2^b for any of the purposes above described as illustrative instances, with relation to the times of operation of the remaining knitting devices are controlled by the form and position on drum 120 of replaceable cams 507 for actuating the thrust-bar 80 460 moving cam 382, and of replaceable cams 517 for actuating the thrust-bar 26 for moving slide 2.

Fig. 5 shows a typical set of indications carried by drum 120 for co-operation with 85 the supplemental cams as described in connection with Fig. 4 to make a stocking of the kind shown and claimed in my said Patent No. 1,113,166, comprising beside cams 507 and 517 a ring of cams 500 for operating 90 mechanism for the local control of stitch length and a device for closing the yarn-feeding gap in latch-ring 550; a cam 501 for operating a slicing yarn guide; cams 502, 503, 504, and 505 for operating other yarn 95 guides; cams 506 for operating clamp and cutter mechanism 601; cams 508 for a yarn-take-up device, cams 509 for operating switch cam 415 and picker 680; and cams 511, 512, 513 and 516 for controlling the 100 stitch-length at various parts of the fabric.

In order to operate slide 2 as explained in connection with Figs. 6 to 13, a cam 517 Fig. 19 having steps for adjusting slide 2 to positions II and III of Fig. 4 may be 105 preceded by a cam 517^a lower than either step, to move said slide to the position shown in Fig. 7.

A preferred type of jack is illustrated in Figs. 14 and 15, those jacks *j*¹ and *j*² for the 110 upper groove 365 having operating butts in the middle of their length and beveled lower ends, to enable the jacks to straddle the widest open space in the cam ring against which their faces may be thrown centrifugally. Contact of the jacks with the smooth inner face of the cam-ring is sufficient to retain them in the needle-grooves, which they fill when in place.

To provide access to the jacks for changing them or removing broken parts, as shown in Figs. 1 and 18, cam ring 271 is cut away at 272 to receive a segmental gate 26 through which grooves 364 and 365 extend. Said gate 26 is provided with a flange 27 attached by hold-down screws 28 to flange 270 of ring 271. The cut at 272 extends outward to enable gate 26 to be moved outward upon releasing screws 28, to disengage the jack butts, leaving the gate free to be lifted away. 130

When the machine is employed for making and ejecting a succession of articles, a stationary friction device for causing the free end of the article to twist and remain central of the cylinder 260 and column 280 is useful to prevent the article clinging at the needles when cast off. A convenient form of this device is illustrated in Fig. 2 at 405, comprising a tubular sleeve extending upward within the needle cylinder and without the forming fabric, said sleeve being supported by an arm 406 fast to the column 280, but I may employ for this purpose the device comprising a relatively fixed arm such as 406 extending upward within the needle cylinder, as also disclosed in my said application Serial No. 766,401.

To coöperate with needles which are returned to action after a season of idleness, such as the needles having long jacks ⁷³, when said needles are restored to action by the removal of cam 2^a, I provide a brush latch opener for needles advancing along the incline 5, as indicated at 425 in Figs. 16 and 17. Such a latch opener may be the same as that disclosed and claimed in my application Serial No. 845,845 filed June 18, 1914.

It will be observed that by the aid of the devices described in connection with Figs. 6 to 13, sections of fabric for instance such as welt fabric knit on alternate needles, and a following section such as body fabric knit on the intervening needles, are begun and ended at the region of the leading long butt needle ³¹⁹, the device of the elongated cam 2^b enabling one or more courses or any multiple thereof to be knit with any adjustment or arrangement of idle and operative needles permitted by cam 382 and the cams 2^a and 2^b.

It will also be observed that the welt fabric, or any other desired section of fabric may be knit upon a series of needles alternating with the series of needles employed for knitting a following section of the fabric, thereby making each of said sections of the same number of needle wales, the following section of fabric having needle wales corresponding to sinker wales of the preceding section.

What I claim is:

1. A knitting machine having needles and means for knitting an extent of fabric at recurrent needles during retention of loops at intervening needles, in combination with means for casting off the loops at said recurrent needles during retention of the fabric at said intervening needles.

2. A knitting machine having needles and means for knitting fabric at recurrent needles thereof only, acting to cause intervening needles not to knit during formation of said fabric, in combination with means for casting off said fabric from said recurrent needles, means for causing said intervening needles to retain the fabric when it

is cast off of said recurrent needles, and means for knitting on said intervening needles in continuation of the fabric retained by them, whereby to form a fabric or article having sections respectively knit on different intercalated series of the same needles.

3. A knitting machine having latch needles, stitch cams, and means for separating the needles into two or more intercalated series, said means acting on one of said series only to clear their latches and means for causing another of said series normally to enter the stitch cams to knit, in combination with means adjustable to cause said first mentioned series to knit or to cast off at the stitch cams.

4. A knitting machine having needles, stitch cams, means for separating the needles into two or more intercalated series, adapted to cause both of said series normally to enter the stitch cams to knit, in combination with means operative at predetermined times on the needles of one of said series after their separation to cause the needles of said series to knit or to cast off.

5. A knitting machine having needles, stitch cams, yarn feeding means, and means for separating the needles into two or more intercalated series, means operative at predetermined times to cause one of said series to enter the stitch cams to knit or to pass the stitch cams while retaining their loops, in combination with means to cause the other series to knit or to cast off at predetermined times.

6. A knitting machine having needles and means for knitting a welt on recurrent needles only during the retention of withheld loops on other needles, in combination with means for casting the fabric from needles engaged in knitting the welt, and means for knitting fabric on said other needles during retirement from operative movement of said recurrent needles.

7. A knitting machine having needles and means for knitting a predetermined extent of fabric for a welt at recurrent needles during retention of withheld loops at other needles, in combination with means for knitting a uniting course and means for subsequently casting off the loops at said recurrent needles during retention of the fabric at said other needles.

8. A knitting machine having needles and means for knitting fabric for a welt at recurrent needles during retention of withheld loops at other needles, in combination with means for knitting a uniting course at said recurrent and said other needles, means for knitting locking fabric at and for casting off the loops from said recurrent needles, during retention of the fabric at said other needles, and means for knitting attached fabric at said other needles.

9. A knitting machine having needles and means for knitting at recurrent needles only during retention of loops at other needles in combination with means acting thereafter 70
- 5 to knit on all the needles, and means for subsequently casting off the loops at said recurrent needles, and means for thereafter knitting attached fabric at said other needles only.
- 10 10. A knitting machine having needles and means for knitting a selvage structure on the bare needles comprising a device for causing the yarn to be taken at successive courses by recurrent needles and by all the 75
- 15 needles respectively, in combination with means for knitting at said recurrent needles and means for casting off the loops from said recurrent needles, the fabric being retained for further knitting at said other 80
- 20 needles.
11. A knitting machine having independent needles, a stitch cam adapted to actuate all of the needles to knit when the needles are normally positioned, means for separating the needles from their normal position 85
- 25 into intercalated differently positioned series, means for causing each of a plurality of said separated series at predetermined times to knit or to pass beneath the stitch 90
- 30 cam without knitting, and means for casting off the stitches of one of said series.
12. A knitting machine having independent needles, stitch cams, yarn feeding means, and means for separating the needles into 95
- 35 two or more intercalated series, means movable to cause one of said series either to enter the stitch cams to knit, or to pass the stitch cams without taking new yarn, in combination with means movable to cause 100
- 40 the other series to knit or to cast off.
13. A knitting machine having needles and stitch cams, and means for predetermining independently the operation of series of said needles intercalated among each other 105
- 45 rising independently movable jacks, actuating means for independently moving intercalated series of jacks and their needles, and means co-operating with the independently positioned needles to cause their different actuation.
14. A knitting machine having latch needles, stitch cams, and means for returning all the needles therein to the same normal position at each course knit, in combination with means adapted to separate the needles into series, means for determining the passage into the stitch cams or into an idle cam-path of each of said series independently, and means adapted to clear the 115
- 55 latches of one of said series of needles prior to entrance of the needles into the idle cam-path, whereby to cause the needles of said series to drop their stitches.
- 60 15. In a knitting machine, needles and independently movable jacks, actuating means 120
- 65 for separately moving different series of jacks to differently position their needles and cam mechanism having different operating paths for the differently positioned needles.
16. In a knitting machine means for separating for different operation series of needles intercalated among each other comprising independently movable jacks, means for actuating series of jacks intercalated among each other independently, and supplemental 125
- 70 cam mechanism co-operating differently with the series of needles separated by the operation of said actuating means.
17. A cam ring for an independent needle knitting machine comprising stitch cams 80
- 75 and a plurality of cam grooves for the actuation of needle positioning jacks, said cam grooves having active portions at different circumferential positions.
18. A knitting machine having in combination a needle carrier, independent needles, a cam ring and stitch cams thereon, independently movable needle jacks for the needles having operating butts at different distances from their needle engaging portions, 85
- 80 and a plurality of cam grooves in said cam ring for moving to different positions different series of said jacks and the needles 90
- 85 operated thereby.
19. A knitting machine having in combination stitch cams, a needle carrier and needles, means for vertically separating the needles into intercalated series, and a supplemental cam device operating on one or more of said separated series ahead of the 95
- 90 stitch cams comprising a needle depressing member and a following needle advancing member, and means for advancing some of the needles after their passage of said depressing member and separating means into 100
- 95 contact with said advancing member.
20. A knitting machine having independently movable latch needles and knitting cams therefor comprising stitch cams and means for retaining needles between successive passages of the stitch-cams at a position in which their latches are not cleared through the previous loops, in combination with means for selectively advancing certain of said needles to clear their latches in 105
- 100 advance of the stitch cams, means movable into and out of contact with the said needles and other needles for depressing them to take a path beneath the stitch cams, and means for restoring said other needles to 110
- 115 position to enter the stitch cams.
21. A knitting machine having stitch cams, independent needles, and means for holding said needles between passages of the stitch cams at the tuck position, in combination 120
- 125 with means acting ahead of the stitch cams to advance and clear the latches of recurrent needles, a supplemental depressing cam for depressing all of the needles to take an idle path beneath the stitch cams, and means to 130

restore certain depressed needles only to position to enter the stitch cams.

22. A knitting machine having stitch cams, independent needles, and means for holding said needles between passages of the stitch cams at the tuck position, in combination with means acting ahead of the stitch cams to advance and clear the latches of recurrent needles, a supplemental depressing cam for depressing all of the needles to take an idle path beneath the stitch cams, means to restore certain depressed needles only to position to enter the stitch cams, and an independently adjustable supplemental cam for causing needles in a normal position to take said idle path.
23. In a knitting machine, the combination with latch needles of stitch cams yarn feeding means and means for selectively clearing the latches of recurrent needles only acting ahead of the stitch cams, a movable depressing cam for retiring said recurrent needles without taking new yarn, whereby said needles may be caused to cast their loops, or to enter the stitch cams and knit, and a device for positioning intervening needles either to knit or to pass the stitch cams without contact with the new yarn while retaining their loops.
24. A knitting machine having in combination needles, a stitch cam and means for selectively causing certain of the needles to knit at the stitch cam or to pass beneath said stitch cam without knitting comprising a supplemental cam device having separated needle advancing and needle depressing members, and means coacting with certain of the needles only to move them through the space between said members to cause their entry into the stitch cams.

25. A knitting machine having in combination needles arranged in series having operating butts of different length, a stitch cam and means for selectively causing certain of the needles to knit at the stitch cam or to pass the stitch cam without knitting comprising a supplemental cam device having separated needle advancing and needle depressing members, means for advancing said cam device into contact with the needles in a plurality of stages whereby the cam is positioned first to act on the leading needle of a series having longer butts, and means acting on certain of the needles only to move them through the space between said members when said cam device is in operative position.

26. A knitting machine having in combination needles arranged in series having operating butts of different lengths, a stitch cam, a supplemental depressing cam, and means for entering said depressing cam during the passage of needles having shorter butts to first encounter and move needles

having longer butts, means to independently advance some of the needles only, and means comprising a depressing cam, an advancing cam and devices to move said latter cam to first contact with a series of needles independently advanced having longer butts, thereby to remove them from contact with said first mentioned cam.

27. A knitting machine having a needle carrier and needles therein having butts of different lengths, a supplemental cam device for determining the position of one or more intercalated series of said needles comprising a depressing member and an advancing member, movable with respect to said carrier, one of said members being fixed with respect to the other member and nearer said carrier in all positions, in combination with means for moving certain of the needles from a depressed position into contact with said advancing member and means for moving said cam device to engage one of said members only with needles having longer butts.

28. In a knitting machine having devices for starting knitting on the bare needles, a needle cylinder, and a device for maintaining the forming end of a new section of fabric in a central position in said cylinder comprising means to twist the fabric.

29. In a knitting machine, a needle cylinder, and a device for maintaining the fabric in a central position in said cylinder comprising means within said cylinder, and means to cause relative rotation of said means and said cylinder, whereby to twist the forming fabric.

30. In a knitting machine having devices for starting knitting on the bare needles, a needle cylinder, and a device for maintaining the fabric in a central position in said cylinder comprising a tube extending within said cylinder and means to support said tube, said tube and cylinder being relatively movable whereby the forming fabric is twisted by its friction with said tube.

31. In a circular knitting machine having needles, means acting to separate the needles into different series, devices for knitting longitudinally successive fabric sections on the different series of said needles, and means for beginning and ending said sections of fabric at predetermined courses in the same adjacent needle wales.

32. A circular knitting machine having needles and devices for separating the needles and for knitting longitudinally successive sections of fabric respectively on different intercalated sets of said needles, in combination with means for beginning knitting on each set at adjacent needles.

33. A knitting machine having in combination needles, and means adapted automatically to knit on intercalated series of

needles in succession connected sections of plain fabric each containing the same number of knit wales, one section having needle wales corresponding to sinker wales of a 6 succeeding section.

In testimony whereof, I have signed my

name to this specification in the presence of two subscribing witnesses.

ROBERT W. SCOTT.
